UNITED STATES PATENT OFFICE

2,373,556

FIGURE TOY

George A. Fullerton, Clarendon, Pa.

Application April 26, 1944, Serial No. 532,810

3 Claims. (Cl. 46—205)

This invention appertains to new and useful improvements in toys and more particularly to a wheeled figure toy such as will offer considerable amusement to children.

The principal object of the present invention is to provide a wheeled toy in the form of a wheel barrow and including movable figures adapted to be operated by the wheel of the wheel barrow.

Other objects and advantages of the invention will become apparent to the reader of the following description.

In the drawings—

Figure 1 represents a fragmentary side elevational view of the toy.

Figure 2 is a front elevation.

Figure 3 is a fragmentary top plan view.

Referring to the drawings wherein like numerals designate like parts, it can be seen that numeral 5 denotes the handles of the structure from which side walls 6 and a head wall 7 rise. Interposed between the hand bars 5 is a floor 8 which along with the side walls 6 and the head wall 7 defines the box portion of the wheel barrow.

The bottom 8 extends forwardly and is bifurcated to provide forwardly projecting and spaced furcations 9, 9 through which an axle pin 10 is disposed, this pin serving as an axle for a wheel 11.

The wheel 11 is provided with a plurality of laterally projecting pins 12 adjacent the periphery thereof and uniformly spaced circumferentially.

Mounted on the upper portion of the head board 7 are figures 13 and 14 which in the present instance simulate an elephant and a mouse, respectively. Each of these figures has a depending support pivotally secured as at 15 and 16, respectively, to the head board 7.

Rods 17, 18 extend downwardly from the supports as shown in Figure 2 and have lateral portions *a* disposed into openings *b* at the inner end portions of arms 19, which arms are provided with transverse openings at their inner ends through which a rod or pin is disposed. The forward side of the head board 7 has a ledge 21 thereon notched as at 22, 22 to accommodate the inner ends of the arms 19, and as is apparent in Figure 3, the rod or pin 20 is held in place by staples or the like 23.

The arms 19 are made of reasonably heavy material so that they will gravitate on to the pins 12 carried by the wheel 11.

It can now be seen, that as the wheel barrow is pushed and the wheel 11 rotates, the arms 19 will drop from one pin 10 to the next and the swinging action of the arms 19 will actuate the connecting rods 17, 18 and animate the figures 13 and 14, to the end that the appearance is that one of the figures is chasing the other.

While the foregoing specification sets forth the invention in specific terms, it is to be understood that numerous changes in the shape, size and materials may be resorted to without departing 15 from the spirit and scope of the invention as claimed hereinafter.

Having described the invention, what is claimed as new is:

1. A figure toy comprising an elongated handle structure, a wheel mounted on the handle structure, an upright on the handle structure, a movable figure carried by the upright, lateral projections on the wheel, a swingable arm on the upright structure adapted to strike against the projections on the wheel and a link connection between the figure and the arm.
2. A figure toy comprising a wheel barrow including a wheel and a front wall, a pair of rockable figures on the said front wall, a pair of arms swingably carried by the front wall, lateral projections on the wheel against which the arms can gravitate and link members between the arms and the figures.
3. A figure toy comprising a wheel barrow including a wheel and a front wall, a pair of rockable figures on the said front wall, a pair of arms swingably carried by the front wall, lateral projections on the wheel against which the arms can gravitate and link members between the arms and the figures, said wheel barrow including a bottom provided with a forward projecting portion, said projecting portion being bifurcated to accommodate the wheel and having notched out portions to accommodate the said pins.
